US00D894608S

(12) **United States Design Patent** (10) **Patent No.:** **US D894,608 S**
(45) **Date of Patent:** **** Sep. 1, 2020**

(54) **PANEL FOR A SUITCASE**

(71) Applicant: **FTI GROUP (HOLDING) COMPANY LIMITED**, Grand Cayman (KY)

(72) Inventor: **Jerry Moon**, Taipei (TW)

(73) Assignee: **FTI GROUP (HOLDING) COMPANY LIMITED**, Grand Cayman (KY)

(**) Term: **15 Years**

(21) Appl. No.: **29/650,263**

(22) Filed: **Jun. 5, 2018**

(51) LOC (12) Cl. **03-01**

(52) U.S. Cl. **D3/321**
USPC ....

(58) **Field of Classification Search**

(57) **CLAIM**

The ornamental design for a panel for a suitcase, as shown and described.

DESCRIPTION

FIG. 1 is a front perspective view of a panel for a suitcase showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a cross-sectional view taken along line 9-9 of FIG. 2.

1 Claim, 7 Drawing Sheets
